UNITED STATES PATENT OFFICE

ROBERT HENRY DAVIS, OF LONDON, ENGLAND

BREATHING APPARATUS

Application filed August 20, 1929, Serial No. 387,119, and in Great Britain May 21, 1929.

This invention relates to breathing apparatus of the kind employing a breathing bag in which a chemical substance is employed to absorb the carbon dioxide content of the expired breath of the user of the apparatus, and also having within the bag one or more comparatively small and light capsules filled with a respiratory gas, such as oxygen, or air, or a mixture of air and oxygen, under pressure, and provided with means whereby the said gas may be liberated by force applied externally of the said bag.

Hitherto the chemical substance above referred to has been such that it is capable of evolving oxygen for respiratory purposes when the moisture contained in the expired breath of the user of the apparatus makes contact therewith.

The object of the present invention is to dispense with the use of chemical substances capable of evolving oxygen in the manner described, as it is found that the liberation of the oxygen therefrom is comparatively slow.

According to the present invention there is provided a breathing apparatus comprising a breathing bag, a canister open to the said bag, and charged with a chemical substance which reacts only to absorb carbon dioxide, a mouth-piece for the user of the apparatus connected to the said canister so that his breath will pass through the latter into the bag, and at least one capsule charged with respiratory gas, such as oxygen, or air, or a mixture of air and oxygen, under pressure, disposed within the bag and capable of being unsealed to liberate the gas into the bag.

In a suitable arrangement for carrying the invention into practice, a chemical absorbent for carbon dioxide, for instance, soda lime or caustic soda, or a mixture of both of said substances, is disposed within a canister arranged in communication with a mouth-piece and a breathing bag containing the capsule or capsules. A cylinder containing compressed oxygen is arranged outside the said bag and the outlet of the said cylinder connected to the said bag by a tube so that by operating a sealing valve of the said cylinder a supply of oxygen can be furnished to the bag, in

addition to or in place of that furnished by the capsule or capsules.

The canister may be placed either outside or within the breathing bag and connected by a tube to the mouthpiece.

The breathing bag may also advantageously be fitted with a connection whereby it can be charged with respiratory gas such as oxygen from any suitable source of supply independently of the capsule or capsules contained within the said bag and of the oxygen cylinder above referred to.

The breathing bag may also be fitted with a valve capable of being closed when the apparatus is used in a poisonous atmosphere and of being opened when the apparatus is used under water to allow of the escape of excess gas.

To enable the invention to be clearly understood, the same will be described with reference to the accompanying drawings, in which:—

Figure 1 is a sectional front elevation of breathing apparatus constructed in accordance with the invention.

Figure 2 is a sectional side elevation of the apparatus, the section being taken on the line 2—2 of Figure 1, and,

Figures 3 and 4 are, respectively, a sectional elevation and a plan view of the canister for the chemical absorbent, detached from the apparatus.

Referring to the drawings, *a* is a breathing bag made of flexible gas-tight material, *b* is a capsule arranged within the bag *a*, the said capsule being filled with a respiratory gas such as oxygen, or air, or a mixture of oxygen and air, under pressure, and having its outlet *c* sealed with a closed tube *d* designed to be broken off to allow of the escape of the compressed gas into the bag *a*. To enable the breaking of the tube *d* to be easily effected, it is furnished with a screw-thread, and a fitting *e* is arranged to project through and within the bag *a* and be secured to a side wall *a'* of the latter by a nut *f*, the said fitting being formed with a screw-threaded hole *g* to receive the tube *d*. If, therefore the portion of the fitting *e* exterior to the bag be held by one hand of the user of the apparatus, pres-

sure applied on the exterior of the bag by the other hand can be exerted on the capsule and cause rupture of the tube d , to allow the compressed gas in the said capsule to expand into the said bag.

h is a canister containing a chemical capable of reacting only with carbon dioxide, for instance, soda lime, or caustic soda, or a mixture of both said substances, which is confined between layers i , i^1 of wire gauze or the like, the layer i being located adjacent an opening j in the upper end of the canister and the layer i^1 fitting within the open lower end k of the same, the said opening j being surrounded by an upwardly projecting rim j^1 .

The said canister is arranged within the bag a and is secured to a portion a^2 of the upper wall of the said bag, the opening j at its upper end being connected by a flexible tube l to a mouth-piece m on which is mounted a nose-clip m^1 . The connection of the canister to the tube l is by way of a hollow fitting n having a tubular extension o to which the said tube l is attached, and being secured to the canister h by a screw p , the upper wall a^2 of the bag a being formed with an opening at a^0 to receive the rim j^1 on the canister and clamped around the said opening between the fitting n and the canister so that the said screw serves the double purpose of securing the tube l to the said canister and the latter to the bag.

The portion a^2 of the bag containing the opening a^0 is formed of elastic material, such as rubber, so that by stretching the said opening the canister can be placed in or removed from the bag.

The canister h , instead of being arranged within the bag a , as described, may be arranged exterior thereto, with its lower end secured to and opening into the said bag.

q is a cylinder containing compressed oxygen, air, or a mixture thereof, arranged outside the bag a in a pocket r on an extension flap s on the bag a , the outlet from the said cylinder being connected by a tube t to the part of the fitting e which projects through the said bag, this portion of the said fitting being formed tubular and provided with a cross passage u in the part thereof located within the said bag. By this arrangement, if the sealing valve v of the cylinder q be manipulated, the compressed gas within the said cylinder can be allowed to expand into the bag a by way of the tube t and the passage u in the fitting e .

The bag a is also fitted with a connection fitting whereby it can be charged with respiratory gas, such as oxygen, air, or a mixture thereof, from a supply unattached to the bag a and independently of the supplies afforded by the capsule b and the cylinder q which are carried by the said bag. This connection fitting is indicated at x and opens directly into the canister h and is secured within an open-

ing in the bag a by the nut x^1 , a non-return valve y being arranged within a part x^2 screwing on to the said fitting. The said fitting part x^2 is formed with a spigot x^3 which is screw-threaded to enable the supply tube 70 from the source of the compressed gas, not shown, to be connected thereto, say, by a union joint.

Although the last described supply of compressed respiratory gas has been described as being supplied to the bag a by way of the canister h , it is to be understood that it may be supplied directly to the said bag.

z is a non-return valve connected to the bag a and made in the form of a flattened tube of rubber, or like elastic material, having slits z^1 , z^2 for the escape of excess gas from the said bag against external pressure which tends to close the valve by pressing the flat sides of the said tube together.

From the foregoing it is to be understood that the user of the breathing bag has three separate sources of respiratory gas upon which to rely.

The valve z may be arranged so that it can be easily closed, for example by means of a tap or clip, if the apparatus be used in a poisonous atmosphere. Or, instead of the flexible valve z a non-flexible non-return valve may be employed to allow the escape 95 of the excess pressure, an ordinary tap being employed to close the outlet orifice when the apparatus is used in poisonous atmosphere.

a^3 a^4 and a^5 a^6 indicate pairs of straps on the bag a for securing the said bag and its fittings in position for use, the straps a^3 extending around the neck, and the straps a^4 around the body of the user.

a^5 a^6 are a pair of straps on the mouthpiece m which are secured around the head of the user.

It is to be understood that the canister h as shown, preferably comprises the device described in the specification of the co-pending British patent application No. 22,310, dated 110 the 19th July, 1929.

Claims:

1. A breathing apparatus, comprising a breathing bag, a canister containing an absorbent of carbon dioxide arranged in communication with said breathing bag, a mouthpiece operatively connected thereto, a cylinder charged with a respiratory gas under pressure in valve-controlled communication with said breathing bag to furnish the normal supply of breathing gas to said bag, and at least one capsule charged with a respiratory gas under pressure disposed within the said breathing bag in such a position as to be breakable to liberate an emergency supply of gas into the said breathing bag by a wrenching movement applied from the exterior of said bag.

2. A breathing apparatus, comprising a breathing bag, a canister containing an ab- 130

sorbent of carbon dioxide arranged in communication with said breathing bag, a mouthpiece operatively connected thereto, a cylinder charged with a respiratory gas under pressure, a fitment in communication with said breathing bag, a valve for controlling the flow of the normal supply of breathing gas from said cylinder to said fitment, and at least one emergency-gas capsule mounted upon said fitment and disposed within the said breathing bag in such a position as to be breakable to liberate an emergency supply of gas into the said breathing bag by a wrenching movement applied from the exterior of said bag.

3. A breathing apparatus, comprising a breathing bag, a canister containing an absorbent of carbon dioxide arranged in communication with said breathing bag, a mouthpiece operatively connected thereto, a cylinder charged with a respiratory gas under pressure, a fitment in communication with said breathing bag for controlling the flow of the normal supply of breathing gas from said cylinder to said fitment, and at least one capsule charged with a respiratory gas under pressure detachably mounted upon said fitment and disposed within the said breathing bag in such a position as to be breakable to liberate an emergency supply of gas into the said breathing bag by a wrenching movement applied from the exterior of said bag.

ROBERT HENRY DAVIS.
